UNITED STATES PATENT OFFICE.

CHARLES C. CROSS, OF PHILADELPHIA, PENNSYLVANIA.

GAME.

Application filed July 11, 1925. Serial No. 42,886.

To all whom it may concern:

Be it known that I, CHARLES C. CROSS, a citizen of the United States of America, residing in the city of Philadelphia, State of Pennsylvania, have invented certain new and useful Improvements in Games, of which the following is a specification.

The invention relates to a game known as Fort, consisting of the board to be described, a number-indicating chance device as dice or a spinner, and soldiers, a suitable number to each player. In the form of the game described, each player has four soldiers.

The plot or theory of the game is that the soldiers have been camping in an outpost and are trying to reach the fort.

In the accompanying drawing I have illustrated a board for use in playing the game of the invention.

20 In the drawing—

Figure 1 is a plan of the board showing the layout of the game diagrammatically.

Figure 2 is a front elevation of the board showing the thickness thereof and the hinge.

25 Figure 3 is a similar elevation showing the board folded.

Figure 4 shows the dice and soldiers.

The board "B" as shown is square, though it may be in any preferred form. At the center is a fort 1 which may be in four divisions 1', 1'', 1''', 1''''', one for each player, and at the respective corners are four camps or outposts 2, the latter with the fort forming on the board a figure in the nature of a Maltese cross. The board also includes tunnels 3, entering the fort from each side intermediately of the adjacent camps from neutral grounds 5, between each of the two adjacent outposts or camps and along the outer margin of the board. The neutral grounds or areas are four in number, one at each side of the board.

40 The fort as aforesaid comprises a central area 1, and the board with the exception of the neutral ground and the outposts or camps 2, is marked out with a series of circular lines concentric with the fort and of uniformly varying radius. In the illustration there are eight such circles dividing the area between the fort, the adjacent outposts and the neutral ground into a series of concentric arcuate strips or spaces 6.

One of these arcuate spaces indicated by reference character 7 is marked with circles 8 indicating that only two checkers or soldiers may occupy the trench at one time. This space is the trench. The area between the trench or trenches and the fort, indicated by reference character 9, and the portion 10 within the inner circle immediately adjacent the fort at the inner end of each outpost, is known as the trail by which the soldiers progress from one trench to the other, the outer area beyond the trenches, i. e., between the trenches and the neutral ground and between the adjacent outposts indicated by reference character 13, is known as no-man's land.

In Figure 4 I have shown dice 15 and soldiers 16. In playing the game in the preferred form, the players, as aforesaid, are provided with two dice or other number-indicating chance device, and four checkers or soldiers. There may be two, three or four players, each playing independently or as partners in the case of four players, the respective partners sitting oppositely. The players throw for turns and the player throwing the highest has first go, the plays or turns progressing from player to player in rotation to the right. A double entitles the player to a second throw, and each player must enter a soldier whenever he throws a six, until all four soldiers have been entered. A double counts 14 and may be divided by using the combination as shown on the opposite side of the dice. The third double throw in succession counts only as shown on the face of the dice and terminates the player's turn or play.

Each player has allotted to him a corner of the board and an individual outpost or camp where his four soldiers are placed until entered. Whenever he throws a six, he places one man in the trench 7 immediately to the left of his camp, using the numbers thrown on each dice other than the number 6 to advance such man as he may select, and after all of the men are entered, using all of the respective numbers through advancing the man to whom the numbers thrown are applied one circle for each unit of the number thrown. The trenches are eight in number and in them the soldiers are safe from

- capture as they are likewise in the neutral ground. Blocks cannot be formed in neutral ground and as many soldiers as desired may be placed in the neutral area. The circles are counted from the trenches inward by the trail two steps to the wall of the fort and then to the right, each line crossed being a step or unit. The player crosses the end of his outpost and then moves outward radially to the end of no-man's land, proceeding across the neutral ground to his right to the next line of spaces in no-man's land on the other side of the tunnel and adjacent the next outpost, which line of spaces or steps is traversed inwardly in radial direction to the fort wall and hence around the board in counter-clockwise direction to the tunnel at the player's left of his own outpost or camp. When the soldier reaches this tunnel, he is advanced step by step as already described, until he enters the fort, the final entrance to the fort counting a single step or unit. A double permits the advancing of one or all the soldiers, the total of fourteen, the double being divided as aforesaid by using the combination on the opposite side of the dice.
- A retreat or backward move can be made only to capture a soldier or to form a block or to enter a trench or neutral ground. Soldiers cannot retreat back of their entrance trenches.
- By a block is meant that two soldiers of the same color or partners on the same space form a block. Blocks can only be formed in the trenches and no-man's land, not on neutral ground. A block cannot be passed by any soldier. Only two soldiers can occupy the same space at the same time, except on neutral ground, where as many as desired may be placed.
- Capture can only be made when the number as indicated by one or both dice brings the soldier to the exact space occupied by an opponent. When a soldier is so captured, he is returned to his camp or outpost and must be reentered. A soldier may retreat the number of spaces as shown on one dice, if by so doing it brings him to a trench on neutral ground, then advance a number of spaces as shown on the other dice to make a capture, or this movement may be reversed.
- The fort is the centre and final haven of the soldiers. The exact numbers indicated by the spaces in the tunnel must be thrown for entry. The fort counts as one space. The player or partners first getting all his or their soldiers in his or their fort or forts, wins the game.
- The path followed by the soldiers is radially outward from the starting point to the neutral ground, and after the neutral ground has been crossed, the trail is radially inward, thence circumferentially across the area to the next radial trail, thence radially out-

ward to the next neutral ground, etc., until the neutral ground is reached from which the player's tunnel may be entered. This tunnel leads to the player's fort, which is the final position to be reached.

70

The rules relating to the various areas and moves are as follows:

Each player enters a man from the camp area to the starting point on the trail when he succeeds in throwing a six with the dice, 75 which represents six bugle blasts. If six is a combination of 5 and 1, 2 and 4, or 3 and 3, enter one soldier; if six is thrown with 1, 2, 3, 4 or 5, enter one soldier and advance to the right the number of spaces as indicated on the other dice; if double six is thrown, enter two soldiers. A soldier in camp must be entered when six is thrown.

80

The camp or outpost is the starting point and the place to which soldiers are returned when captured. The soldiers are supposed to be camping in an "outpost" and trying to reach their company in the fort (center).

85

The trenches are eight in number and in them the soldiers are safe from capture. 90 The entrance trenches are to the left of each player. Two soldiers of the same color or partners in the same trench form a block. Only two soldiers of the same color or partners can occupy the same trench at the same time.

95

The neutral grounds are four in number. This space is absolutely neutral and no soldier can be captured therein. It may be occupied by any number of opposing soldiers 100 at the same time. Blocks can not be formed in the neutral ground.

100

The trail is the space between the trenches. There are five spaces in each trail. Soldiers must advance or retreat single file on the 105 trail, hence no blocks can be formed on the trail. Any soldier on the trail may be captured or passed.

105

No man's land is the space between the trenches and neutral ground. There are 110 four spaces in each no man's land. Two soldiers of the same color or partners occupying the same space in no man's land form a block which can not be passed nor can they be captured. A single soldier in no man's land can be captured or passed.

115

The tunnel is the space between no man's land and the fort (center). There are seven spaces in each tunnel. A tunnel can be used only by the soldier entering his fort through this tunnel. A soldier enters the tunnel to the player's left having first completed the course around the board. A soldier can not be captured in his tunnel, but as it is very narrow, soldiers must advance single file. No retreating or passing allowed in the tunnel.

120

An advance is the forward movement of the soldiers. A soldier advances the number of spaces (not lines) as are indicated by the 130

10 65 to the next radial trail, thence radially out-

5 dice, omitting the space on which he stands. Neutral ground counts as one space. Advances may be the total of the two dice with one soldier, or two soldiers each moving the exact number of spaces as shown by one dice. A double permits the advancing of one or all the soldiers as shown under caption dice. A player moves his own soldiers only and can not move those of his partner.

10 A retreat is the backward movement of the soldiers. A retreat can be made only to capture a soldier, or to form a block, or to enter a trench or neutral ground. Soldiers can not retreat back of their entrance trenches. 15 The movement is as indicated under caption "Advance".

A capture can only be made when the number as indicated by one or both dice bring the soldier to the exact space occupied 20 by the opponent. A soldier may retreat the number of spaces as shown on one dice, if by so doing it brings him to a trench or neutral ground and then advance the number of spaces as shown on the other dice to make 25 a capture, or this movement may be reversed. The captured soldier is returned to camp and re-entered as shown under caption Soldier.

Blocks are formed when two soldiers of 30 the same color or partners are on the same space. Blocks can only be formed in the trenches and no man's land. A block can not be passed by any soldier. Only two soldiers can occupy the same space at the same time.

35 The fort is the center and final objective, the soldiers must enter to win the game. The exact number as indicated by the spaces in the tunnel must be thrown for entry. The fort counts as one space. The player or

partners first getting his soldiers in his fort 40 wins the game.

I have thus described specifically and in detail a single embodiment of my game in order that the nature and manner of playing the same may be fully understood; however, 45 the specific terms herein are used descriptively rather than in a limiting sense, the scope of the invention being defined in the claims.

What I claim and desire to secure by Letters Patent is:

1. A game apparatus including a board bearing a diagram provided with camp areas, neutral grounds between the outer ends of said camp areas, radial tunnel paths 55 from said neutral grounds to the center of said board, a plurality of separate fort areas in the central portion of said board and a radially inward trail area on one side of each camp area and a radially outward trail area 60 on the other side of each camp area.

2. Game apparatus including a board bearing a diagram provided with camp areas, neutral grounds between the outer ends of said camp areas, radial tunnel paths 65 from said neutral grounds to the center of said board, a plurality of separate fort areas in the central portion of said board and a radially inward trail area on one side of each camp area and a radially outward trail area 70 on the other side of each camp area, said game apparatus including chance indicating control means and a plurality of men or pieces for each player, all of permanently 75 fixed value.

Signed by me at Philadelphia, Pennsylvania, this 9th day of July, 1925.

CHARLES C. CROSS.
